Patented July 1, 1913.

UNITED STATES PATENT OFFICE.

CHARLES J. JOLIDON, OF HARTFORD, CONNECTICUT.

MAGAZINE-FIREARM.

1,066,207.

Specification of Letters Patent.

Patented July 1, 1913.

Application filed April 29, 1910. Serial No. 558,464.

To all whom it may concern:

Be it known that I, CHARLES J. JOLIDON, a citizen of the United States, and a resident of Hartford, in the county of Hartford and State of Connecticut, have invented a new and Improved Magazine-Firearm, of which the following is a specification.

My invention relates more especially to that class of firearms in which the action is automatic, that is, self-acting to successively supply cartridges to the barrel, set the hammer and eject the shells after discharge, and the object of my invention, aside from the special objects, is generally to provide a device of this class having numerous novel features of advantage and utility.

One form of device embodying the invention and in the use of which the objects sought may be attained is illustrated in the accompanying drawings, in which—

Figure 1 is a view in side elevation of a firearm embodying my invention, with parts broken away to show construction, the parts being in their normal relative position with the exception of the hammer, which is shown as thrown back, ready for discharge. Fig. 2 is a like view but showing the relative position of the parts immediately after discharge. Fig. 3 is a view in cross-section on plane denoted by dotted line 3—3 of Fig. 1. Fig. 4 is a detail view showing the manner of mounting the repeating check. Fig. 5 is a detail view in section through the front end of the breech-bolt. Fig. 6 is a detail view showing the manner of mounting the safety lock. Fig. 7 is a detail view showing the construction and operation of the safety lock.

The frame of my improved firearm may be constructed of any suitable material and generally of any desired form, including a grip portion 7 and a breech portion 8. The grip portion includes side parts 9 between which is formed in the usual manner a magazine chamber, the latter being closed at the rear by a back-piece 10 containing a substantial portion of the firing mechanism. The breech 8 has a barrel opening 11 and an opening 12 for a breech-bolt. A cover 13 is suitably attached to the frame, closing the opening forming the breech-bolt chamber 14 therein.

It is of advantage in devices of this class that the barrel may be readily removed or

inserted in its place, and that it shall be securely retained therein. I have embodied in my improved firearm means for accomplishing these results. In carrying out this idea the barrel opening 11 is formed on one side with ribs and grooves 15, 16 and the barrel 17 has a raised segment 18 consisting of ribs forming grooves between them, which ribs and grooves mesh with the grooves and ribs in the barrel opening when the barrel is turned to its proper position in the frame, these ribs and grooves extending circumferentially of the barrel as shown in Figs. 1 and 3 of the drawings. In order to removably secure the barrel the opening 11 has a recess 19 on one side of a width to receive the ribs and grooves on the barrel, and the latter has a stop 20 located to engage a stop shoulder 21 on the frame to limit the rotating movement of the barrel as it is being placed in position and to determine the proper position thereof. When the barrel is turned to its proper position the ribs thereon will have passed out of the recess 19 and have their ends preferably located in line with the ends of the ribs 15 forming one side of the recess 19. A key 22 nicely fits the recess 19 to prevent rotation of the barrel from its proper position, and in order to retain the key I provide it with a spring finger 23 having its end shouledered as at 24 to engage notches 25, which construction yieldingly holds the key in place, its outer end having a shoulder 26 which may be reached through a nail groove 27 formed by cutting away a part of the frame, as shown in Fig. 2 of the drawings.

The breech-bolt 28 may generally be of common form and construction, including a breech-bolt frame 29 mounted to slide in the breech-bolt chamber and a tubular projection 30 passing out of the frame through the breech-bolt opening 12. A breech-bolt retracting spring 31 is seated with one end against a support in the main frame in any ordinary manner, and its outer end exerting its force upon the breech-bolt through the medium of a tip 32, cap-pin 33 and breech-bolt cap 34, the latter being secured upon the end of the breech-bolt as by means of interengaging screw-threaded parts and being held from rotation by the pin 33. The pin 33 is frictionally held in its opening, which is constituted in fact by a groove 35.

on the inner face of the cap and registering grooves 36 in the end of the breech-bolt. As a means for frictionally holding the pin the tip 32 is recessed at its outer end as at 5 37, notches 38 in the pin 33 receiving the edges of the recess 37, thus preventing longitudinal movement of the pin. The tip is pressed against the pin so that the notches and edges of the tip will be constantly held 10 in engagement by the breech-bolt retracting spring 31, the force of which, however, is not great enough to prevent removal of the pin by the exertion of a little force.

It is necessary in automatic arms of this 15 class that the opening movement of the breech-bolt shall be retarded long enough after the discharge of a shot, that the gases of explosion may have full effect upon the projectile, and that the rearward movement 20 of the breech-bolt, while commencing soon enough to store sufficient energy in the breech-bolt for its automatic operation, shall not be at so rapid a rate as to allow the powder gases to escape rearward from the 25 chamber in the barrel, and in order to accomplish this result I provide the following retarding mechanism, which insures that the bullet has left the barrel before the opening 30 of the breech is sufficient to allow gases to escape rearward.

A retarding sleeve 39 is placed upon the tubular projection 30 from the breech-bolt; a retarding spring 40 being located within the sleeve and between it and said tubular 35 projection. A retarding sleeve trip 41 in the form of a lever is pivotally mounted on the frame and has a projection forming a cam release 42 extending through an opening 43 in the frame into the path of movement 40 of a cam lug 44 on the breech-bolt. This trip 41 has its end formed to encounter the end of the sleeve 39, in the preferred form of construction and as shown herein a notch 45 being provided in the end of the 45 trip.

In the operation of this part of the device, as a cartridge is exploded the pressure of the gases in the barrel tends through the cartridge shell to move the breech-bolt rearward, but the tension of the spring 31 reinforced by that of the spring 40, both 50 springs exerting their force against the cap 34 fixed upon the breech-bolt, yieldingly retards this opening movement until the 55 cam lug 44 engages the cam release 42, pushing the trip 41 downward and releasing its end from engagement with the sleeve 39. The breech-bolt being now supported only by the tension of the retracting spring 31, 60 yields more readily to the force of the gases in the breech-chamber, such force being exerted against the breech-bolt during the brief interval until the projectile passes from the muzzle of the barrel and thereby 65 relieves the pressure therein. The breech-

bolt under its momentum continues to move rearward until it has fully opened the breech and stored energy in the retracting spring to effect the closing movement in the manner common to firearms of this class.

70

The automatic operation of the pistol cannot begin until a cartridge has been fired, and it therefore becomes necessary to manually open the breech to introduce the first cartridge into the barrel, which must be done by moving the breech-bolt rearward. It will thus be seen from the foregoing description that this rearward movement of the breech-bolt is resisted by both the retracting spring 31 and the retarding spring 40, and if this function of retarding the rearward movement of the breech-bolt was confined to the one spring which retracts the breech-bolt, as in firearms constructed prior to my invention, the force of this spring would require to be overcome at each manual movement of the breech-bolt rearward. By employing the mechanism hereinabove described I am enabled to reduce the power required in the manual operation of the breech-bolt by employing the retarding spring to retard the rearward movement of the breech-bolt only, and I am thus enabled not only to use a retracting spring of just sufficient power to retract the breech-bolt, 95 but to also remove the action of the retarding spring upon the breech-bolt at the time of such manual operation, this being accomplished by means of the finger piece on the sleeve trip or latch 41, by means of which the trip is moved from engagement with the retarding sleeve and this prevents the force of the retarding spring from acting upon the breech-bolt. In the preferred form of construction and as shown herein this finger piece projects into the trigger guard and is located in front of the trigger, so that the trigger finger of the hand holding the grip of the pistol may be applied against the finger piece to operate it, and a comparatively light rearward pressure against the cap on the forward end of the breech-bolt extension at this time will be sufficient to move the breech-bolt rearward and open the breech. A spring, clearly shown in Fig. 1 of the drawings, tends to return the trip or latch to its operative position when the finger piece is released, and on the return forward movement of the breech-bolt to the firing position the energy stored in the retracting spring during the rearward movement of the breech-bolt is sufficient to carry the breech-bolt and the retarding spring and sleeve to their forward positions in which they are at once locked by the locking trip or latch.

It is of importance in firearms of this character that means be provided to prevent inadvertent discharges, as by involuntary pull upon the trigger, unless the breech is

fully closed and the breech-bolt in the forward firing position.

In order to positively prevent firing at all times except when the breech is closed, I employ a safety check 46 pivotally attached in the frame as at 47. This check 46 has a nose 48 arranged to lie within a recess 49 of the breech-bolt when the same is in the forward position. This check 46 has a lug 50 located over a projection 51 of the trigger and preventing upward movement of the back part of the trigger 52. This part of the trigger is preferably in the shape of a stirrup, the projection 51 rising from one or both sides of this rear part, and the magazine 63, of usual form and construction, passing up through the opening between the side parts of the trigger. The trigger has a release shoulder 53 arranged to engage the tail 54 of the sear 55 to release it from the usual notch in the hammer 56. When the parts are in the position shown in Fig. 1, the breech-bolt is in the forward position, the breech is closed and the fire arm is in proper condition for discharge. As the trigger is moved rearward, the shoulder 53 can engage the tail of the sear and move the sear to release the hammer, allowing the latter to be forced forward in the usual manner to strike upon the firing pin. Upon the discharge of the cartridge the force of the explosion causes the breech-bolt to be thrown rearward, whereupon the nose 48 of the safety check 46 is forced downward from the recess 49 of the breech-bolt, carrying the release lug 50 downward against the projection 51 on the trigger, the rear end of the latter also being moved downward. It will be noted by referring to Fig. 2 that if the trigger is now pulled rearward the shoulder 53 will not engage the tail of the sear and therefore the sear will not be moved and no further shots can be fired immediately following the first one from involuntary pressure on the trigger, or from failure to release the trigger, until the breech-bolt has again reached its forward position and the safety check has been moved upward.

In order to provide against the accidental discharge, as from a shock or jar releasing the sear from engagement with the hammer, I provide a lock that holds the sear from disengagement with the hammer. In this embodiment of my invention and as shown herein this lock consists of a slide 58 with its end 59 normally resting back of the sear-tail 54, thus preventing movement of the sear to disengage it from the hammer 56. A lock release 60 is pivotally attached to the frame and has a lug 61 engaging an opening in the slide, as plainly shown in Fig. 1. The upper end of the lock release is normally pressed away from the slide as by a spring 62, the pivot upon which the

release is mounted and the lug 61 being so arranged that by a movement of the upper end of the release 60 toward the slide, by the operation of the trigger, the slide will be moved downward and the end 59 removed from behind the sear-tail. This operation will be readily understood from a glance at Figs. 1 and 2, and it will be noted that the spring 62 rests with one end against the frame, passing through a slot in the slide, which slot is of a length sufficient to permit the required movement of the slide without interfering with the spring.

I do not limit my invention and the scope of the following claims to the accompanying illustration and foregoing description of a device embodying the invention in its preferred form, as these may be departed from to a greater or less extent without avoiding the invention.

The construction of the safety lock constitutes a feature of my invention. This consists of a pin 70 rotatably mounted in the frame, the end of the pin being split as at 71 to form a spring binding feature to hold the pin in place. This pin is cut away on one side forming a recess 72 through which the trigger may pass in one position of the pin. The pin is provided at one end with a knob 73 by means of which it is operated. The pin opening 74 through the frame is enlarged as at 75 forming a shoulder 76 against which the stop 77 on the pin strikes to limit the rotary movement of the pin.

It will be noted that when the parts are in the position shown in Figs. 1 and 2 the trigger may pass through the recess 72, but when the parts are in the position shown in Fig. 4 the finger piece of the trigger will pass under the edge 78 formed by the recess 75 and exert a wedging action, so that the pin will not be turned backward and the trigger will be held against movement.

I claim—

1. A firearm including a frame, firing mechanism, means to receive a projectile for discharge, a breech-bolt arranged to be moved in one direction by the forces of explosion, means exerting force in the opposite direction to retard its movement, a member arranged to receive the thrust of said retarding means, holding means for said thrust receiving member, and connections between the breech-bolt and holding means to move the latter to disengage it from the thrust receiving means.

2. A firearm including a frame, firing mechanism, means to receive a projectile for discharge, a breech-bolt adapted to be moved backward by the forces of explosion, a spring exerting force upon the breech-bolt in the opposite direction, thrust receiving means for said spring, a holder to engage said thrust receiving means and temporarily retain it against movement, and

connections between the breech-bolt and holder to move the latter from engagement with the thrust receiving means.

3. A firearm including a frame, firing mechanism, means to receive a projectile for discharge, a breech-bolt adapted to be moved backward by the forces of explosion, a spring exerting force upon the breech-bolt in the opposite direction, a sleeve encircling a portion of the breech-bolt to receive the thrust of said spring, a holder to temporarily retard the movement of said sleeve, and connections between the breech-bolt and holder to release the latter from engagement with said sleeve in the movement of the breech-bolt.

4. A firearm including a frame, firing mechanism, means to receive a projectile for discharge, a breech-bolt adapted to be moved backward by the forces of explosion, a spring exerting force upon the breech-bolt in the opposite direction, a thrust receiving member for said spring arranged to be moved backward into the breech-bolt opening, a holder to temporarily retard the movement of said thrust receiving member, and connections between the breech-bolt and holder to release the latter from said thrust receiving means in a movement of the breech-bolt.

5. A firearm including a frame, firing mechanism, means to receive a projectile for discharge, a breech-bolt adapted to be moved backward by the forces of explosion, a spring exerting force upon the breech-bolt in the opposite direction, a sleeve surrounding said breech-bolt and inclosing said spring and of a size to enter the breech-bolt opening in the frame, a holder to temporarily retard the movement of said sleeve, and connections between the breech-bolt and holder to release the latter from engagement with said sleeve in a movement of the breech-bolt.

6. A firearm including a frame, firing mechanism, means to receive a projectile for discharge, a breech-bolt adapted to be moved backward by the forces of explosion, means exerting force upon the breech-bolt in the opposite direction, means to receive the thrust of said force, a lever pivotally mounted in the frame and arranged to temporarily hold said thrust receiving means from movement, and means upon the breech-bolt to engage said lever and move it to release it from engagement with said thrust receiving means.

7. A firearm including a frame, firing mechanism, means to receive a projectile for discharge, a breech-bolt adapted to be moved backward by the forces of explosion, means for forcing the breech-bolt in the opposite direction, means to receive the thrust of said force, a trip lever engaging said thrust receiving means to temporarily re-

tard its movement, and a cam lug on the breech-bolt adapted to engage said lever, in a movement of the breech-bolt, and move it to disengage it from said thrust receiving means.

8. A firearm including a frame, firing mechanism, means to receive a projectile for discharge, a breech-bolt adapted to be moved backward by the forces of explosion and having a part projecting from the frame, a spring surrounding said projecting part and exerting force upon the breech-bolt in opposition to the forces of explosion, a sleeve surrounding said projection and spring and of a size to enter the opening in the frame, a trip lever arranged to engage said sleeve, and a cam projection on the breech-bolt adapted to engage the lever and move it to free it from engagement with said sleeve in a backward movement of the breech-bolt.

9. A member movably mounted, a spring exerting force upon said member to move it in one direction, a cap arranged to be engaged with and disengaged from said member by a rotary movement and adapted to receive the thrust of the spring, a pin to hold the cap against turning movement, and means held in engagement with said pin by the thrust of said spring to prevent longitudinal movement of the pin.

10. A member movably mounted, a spring located within said member and adapted to exert its thrust thereon, a cap screw-threaded upon the end of the member to receive the thrust of said spring, a pin extending through the cap and member to prevent movement of said cap, and means adapted to engage the pin and held in engagement therewith by the force of said spring to prevent longitudinal movement of the pin.

11. A firearm including a frame, firing mechanism, means to receive a projectile for discharge, a breech-bolt adapted to be moved backward under the forces of explosion, a spring to move the breech-bolt to its forward position, a cap closing the end of the breech-bolt and adapted to receive the thrust of said spring, grooves in the cap and breech-bolt forming an opening to receive a pin, a pin passing through said opening to prevent movement of the cap, and means to engage said pin and held in engagement therewith by the pressure of said spring to prevent longitudinal movement of the pin.

12. A firearm including a frame, firing mechanism, means to receive a projectile for discharge, a breech-bolt adapted to be moved backward by the forces of explosion, a spring to temporarily retard the movement of the breech-bolt, means for releasing the force of said spring therefrom, a spring to move the breech-bolt to its forward position, a screw-threaded cap located upon the end of the breech-bolt to receive the force of

- both of said springs, a pin projecting through the breech-bolt and cap to prevent rotation of the latter, and means to prevent lengthwise movement of the pin, said means being forced against the pin by the pressure of the spring that returns the breech-bolt to its forward position.
13. A member movably mounted, a spring located within said member to force it in one direction, a cap screw-threaded on the end of said member to receive the force of said spring, a grooved pin engaging said cap and member to prevent rotation of the cap, and means forced by said spring to yieldingly engage the groove in the pin to prevent accidental lengthwise movement thereof.
14. A firearm including a frame, firing mechanism, means to receive a projectile for discharge, a breech-bolt arranged to be moved in one direction by the forces of explosion, a spring exerting force upon the breech-bolt in the opposite direction, thrust receiving means for said spring, and means arranged for manual operation to permit movement of said thrust receiving means and thus remove the force exerted by the spring upon the breech-bolt.
15. A firearm including a frame, firing mechanism, means to receive a projectile for discharge, a breech-bolt adapted to be moved backward by the forces of explosion, a spring exerting force upon the breech-bolt in the opposite direction, a sleeve encircling a portion of the breech-bolt to receive the thrust of said spring, a holder to temporarily retard the movement of said sleeve, and means arranged for manual operation to release said holder from engagement with said sleeve.
16. A firearm including a frame, firing mechanism, means to receive a projectile for discharge, a breech-bolt adapted to be moved backward by the forces of explosion, a spring exerting force upon the breech-bolt in the opposite direction, a sleeve encircling a portion of the breech-bolt to receive the thrust of said spring, a holder to temporarily retard the movement of said sleeve, and means arranged for manual operation and for automatic action to release said holder from engagement with said sleeve.
17. A firearm including a frame, firing mechanism, means to receive a projectile for discharge, a breech-bolt adapted to be moved backward by the forces of explosion, a spring exerting force upon the breech-bolt in the opposite direction, a thrust receiving member for said spring arranged to be moved backward in the breech-bolt opening, a holder to temporarily retard the movement of said thrust receiving member, and means arranged for manual operation to release said holder from said thrust receiving means.
18. A firearm including a frame, firing mechanism, means to receive a projectile for discharge, a breech-bolt adapted to be moved backward by the forces of explosion, a spring exerting force upon the breech-bolt in the opposite direction, a sleeve surrounding said breech-bolt and inclosing said spring and of a size to enter the breech-bolt opening in the frame, a holder to temporarily retard the movement of said sleeve, and means arranged for manual operation to release said holder from engagement with said sleeve.
19. A firearm including a frame, firing mechanism, means to receive a projectile for discharge, a breech-bolt adapted to be moved backward by the forces of explosion, means exerting force upon the breech-bolt in the opposite direction, means to receive the thrust of said latter force, a lever pivotally mounted in the frame to temporarily hold said thrust receiving means from movement, said lever being arranged for manual operation to release it from engagement with said thrust receiving means.
20. A firearm including a frame having a barrel opening and a recess therefrom to receive a projection from the barrel, the frame also having a groove to receive said projection in a rotating movement of the barrel, a barrel having a projection to engage said groove, and a key located in said recess in the frame opposite the projection on the barrel to prevent rotating movement of said barrel.
21. A firearm including a frame having a barrel opening with grooves and recess therein and a recess to receive projections from the barrel, a barrel fitting said opening and having projections to engage said grooves, and a key fitting said recess and located opposite said projections to prevent rotation of the barrel in said opening.
22. A firearm including a frame having a barrel opening and a lengthwise recess at one side thereof and also grooves to receive projections from the barrel in a rotation of the latter, a barrel fitting said opening and having projections to engage said grooves, means for limiting the rotative movement of the barrel in one direction, and a key fitting said recess and located opposite said projections to lock the barrel against rotation in the opposite direction.
23. A firearm including a frame having a barrel opening with a recess therefrom, a barrel fitting said opening, locking means upon the barrel and frame engaged by a rotation of the barrel to lock it in place, a key to hold the barrel against rotating movement, and yielding means upon the key to hold it in place.
24. A firearm including a frame having a barrel opening with a locking recess therefrom and notches in one edge wall of said recess, a barrel fitting said opening, interen-

gaging locking means between the barrel and frame engaged by a rotation of the barrel, a key to lock the barrel against movement, and a spring finger on said key having a shoulder engaging said notches to yieldingly hold the key in place.

25. A safety device including a hammer, a sear, a trigger, a sear lock movable to release the sear, and a lever connected with the lock and mounted independently thereof, said lever being moved to operate the lock in the movement of the trigger to operate the sear.

26. A safety device including a hammer, a sear, a trigger, a slide normally located to obstruct movement of the sear to disengage the hammer, and a lever pivotally mounted in the path of movement of the trigger and

in engagement with said slide and mounted independently thereof.

27. A firearm including a frame and firing mechanism including a hammer, a sear pivotally mounted and a trigger, a slide mounted on the frame and normally located between it and the sear, and a lever pivotally mounted on the frame independently of the slide and having a projection in engagement with said slide and its end in the path of movement of the trigger, whereby the slide is moved from behind the sear.

CHARLES J. JOLIDON.
